UNITED STATES PATENT OFFICE.

RUDY VOINOV, OF CLEVELAND, OHIO.

WRENCH.

Application filed May 25, 1921. Serial No. 472,608.

To all whom it may concern:

Be it known that I, RUDY VOINOV, a citizen of the United States, and resident of Cleveland, in the county of Cuyahoga and

5 State of Ohio, have invented certain new and useful Improvements in Wrenches, of which I hereby declare the following to be a full, clear, and exact description, such as will enable others skilled in the art to which

10 it appertains to make and use the same.

This invention relates to wrenches and more particularly to an improved monkey wrench including a novel arrangement of gripping jaws whereby the wrench may be

15 employed as an ordinary wrench with flat gripping surfaces or as a pipe wrench with corrugated surfaces.

Other objects of the invention will appear upon consideration of the following detail

20 description and accompanying drawings, wherein:—

Figure 1, is a longitudinal section through a wrench constructed in accordance with my invention.

25 Figure 2, is a cross section taken on the line 2—2 of Fig. 1.

Figure 3, is a cross section taken on the line 3—3 of Fig. 1.

Referring to the drawing by numerals, the 30 shank 1 is provided on one edge with a series of teeth 2 and has a jaw 3 fixed on the end of the shank which serves as the stationary jaw. Slidably mounted upon the shank 1 is the ferrule 4 having the movable

35 jaw 5 attached thereto in such a manner that the movable jaw may be longitudinally adjusted on the shank. An adjusting nut 6 is mounted in the ferrule and is provided with helical teeth which engage the teeth 2

40 on the shank so that when the nut is turned the ferrule will be longitudinally adjusted in the manner well known in the art, so that the jaws may be opened and closed.

The jaw 5 flat on its engaging surface is 45 provided with a large recess or socket 7 having reversely inclined sides between which is mounted a wedge shaped gripping member 8 having serrations 9 on the engaging side which are adapted to engage any pipe

50 or member placed between the jaws of the wrench when the same are opened. A substantially square opening 10 is extended transversely through the gripping member 8 and this opening receives the retaining

55 member 11 which extends transversely across the central portion of the recess 7

as shown in Fig. 1, and through the opening 10 so that a limited movement oscillating and vertical is provided for the gripping member 8. Coil springs 12 are interposed between the bottom of the recess and the adjacent edge of the gripping member to normally urge the gripping member outwardly when the wrench is in use so that the serrations 9 will engage any pipe which is placed between the gripping jaws of the wrench, and the flat side of the movable jaw surrounding the member 8, will be adapted to engage a flat surface in the manner of a monkey wrench. In this case the 70 deppressible member, 8, will remain perfectly flat and will not injure the surface of the work, which is important, when engaging the faces of hexagonal soft metal nuts, or other soft metal parts. 75

When the jaws are opened, the member, 8, will rise, and when an irregularly shaped bar or pipe is inserted between the jaws, the member, 8, only will engage that side of the same and will become tilted thereby, as 80 shown in Fig. 4, and when the jaws close the member, 8, will be jammed against the inclined sides of the recess.

The end of the shank 1 opposite to the stationary jaw 3 is provided with a screw 85 threaded shank 14 upon which the handle 15 is mounted, the handle being hollow as clearly indicated in the drawing. A revolvable cap 16 is mounted on the free end of the handle and this cap is provided with 90 an opening having communication with the interior of the handle. A screw driver including a shank 17 is mounted within the handle and is provided at one end with the screw driver blade 18 and at the opposite 95 end with a disk 19 through which a guide pin 20 is passed, the latter being adapted to have its terminals longitudinally moved in grooves 21 provided on the interior of the handle as indicated in Fig. 3. A coil spring 100 22 is interposed between the end of the screw threaded stud 14 and the disk 19 to normally urge the screw driver outwardly when the spring is permitted to expand. A retaining pin 23, however, is provided to 105 extend through the screw driver and through diametrically opposite openings in the handle 15 whereby the screw driver will be held in operative position when not in use. By removing the pin 23, the spring 22, 110 will urge the screw driver outwardly so that the end 18 will extend outwardly beyond

the cap 16 through the opening therein, whereby the screw driver may be employed when desired.

Minor changes may be made in the details 5 of construction without departing from the spirit of the invention or the scope of the claims hereunto appended.

What is claimed is:—

1. A wrench, comprising a shank, having 10 a laterally projecting stationary jaw at one end, a main opposed laterally projecting jaw, movable on said shank towards and from said stationary jaw, and adapted to engage the same, said movable jaw provided with a recess in its engaging face, having oppositely inclined sides, and a loose jaw member mounted in said recess, said loose jaw member being wedge-shaped and adapted to engage with a rounded or 15 irregularly shaped object, and said main movable jaw and stationary jaw member having flat surfaces adapted to engage with flat objects.
2. A wrench, comprising a shank, having 20

a laterally projecting stationary jaw at one 25 end, a main opposed laterally projecting jaw movable on said shank towards and from said stationary jaw, and adapted to engage the same, said movable jaw provided with a recess in its engaging face, having 30 oppositely inclined sides, and a loose wedge-shaped jaw member mounted in said recess, and means for projecting said loose member when said jaws are separated, said loose jaw member adapted to engage with an irregularly shaped or rounded object, and said main movable jaw having flat surfaces surrounding said recess, adapted to engage with flat objects, said loose jaw provided with a transverse opening, and a transverse retaining bar passing through said opening, and into said movable main jaw member. 35 40

In testimony whereof, I hereunto set my hand this 25th day of April, 1921.

RUDY VOINOV.

In presence of—

Wm. M. MONROE,
CHAS. F. SIFE.
